(57) **CLAIM**

The ornamental design for a knob, as shown and described.

DESCRIPTION

FIG. 1 is a top isometric view of my new design for a knob;

FIG. 2 is a bottom isometric view thereof;

FIG. 3 is a sectional view of a top portion of the knob of FIG. 1;

FIG. 4 is a sectional view of the base portion of the knob of FIG. 1, shown separately for ease of illustration;

FIG. 5 is a top view of FIG. 3;

FIG. 6 is a side view of FIG. 3 with the remaining side views being identical thereto;

FIG. 7 is a bottom view of FIG. 3;

FIG. 8 is a top view of FIG. 4;

FIG. 9 is a side view of FIG. 4 with the remaining side views being identical thereto;

FIG. 10 is a bottom view of FIG. 4;

FIG. 11 is a sectional view along line 11—11 in FIG. 5; and,

FIG. 12 is a sectional view along line 12—12 in FIG. 8.

FIGS. 5—12 are shown on a reduced scale.
